D. G. HAY

FINGER RING

Filed Sept. 21, 1922

INVENTOR
DAVID G. HAY

BY
Maurice Sprecherstein
ATTORNEY

UNITED STATES PATENT OFFICE.

DAVID G. HAY, OF CHICAGO, ILLINOIS.

FINGER RING.

Application filed September 21, 1922. Serial No. 589,574.

To all whom it may concern:

Be it known that DAVID G. HAY, citizen of the United States, residing at Chicago, in the county of Cook and State of Illinois, has invented certain new and useful Improvements in Finger Rings, of which the following is a specification.

This invention relates to finger rings. More particularly, it is directed to engagement rings.

Considerable inconvenience and annoyance has resulted from constructions of engagement rings heretofore made when a wedding ring is worn together with the engagement ring, by reason of the fact that the former does not fit snugly against the latter but is spaced therefrom by projecting portions of the engagement ring, such as of the crown portion thereof. Furthermore, the combined wedding and engagement rings have not given a neat and ornamental appearance on the finger, there being a more or less unequal space between the two rings.

One object, therefore, of this invention is to provide an engagement ring of such construction as to permit a wedding ring to be worn on the same finger therewith so as to fit snugly thereagainst and give a combined neat and ornamental appearance when worn together.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claim.

In the accompanying drawing, in which is shown one of various possible illustrative embodiments of this invention,

Fig. 1 is a face view, on an enlarged scale, of an engagement ring embodying this invention;

Fig. 2 is a transverse cross-sectional view cut along line 2—2 of Fig. 1 showing a wedding ring in place fitting snugly against the engagement ring; and

Fig. 3 is a transverse cross-sectional view of the ring shown in Fig. 1 taken along line 3—3 of said figure.

Referring in detail to the drawing, 10

indicates the crown portion and 11 the shank of the ring embodying my invention there illustrated. 12 indicates the setting which may be of any desired ornamental design for receiving the diamond or solitaire 13.

The crown portions of engagement rings, as heretofore made, have projected adjacent the point where the shank meets the crown beyond the shank portion, so that when a wedding ring of corresponding size is placed on the finger in juxtaposition to the engagement ring, the wedding ring could not fit snugly against the engagement ring but was tilted away therefrom adjacent the crown portion by reason of said projecting portions of the crown.

In the present construction, I preferably shape the lower portion of the crown so as to taper or to be inclined or curved concavely from a point such as 14 above the shank toward the point as at 15 where the shank commences. The tapering or inclined portions 16, 16^a are preferably made symmetrical with the shank so as to provide a neat construction, and so that the wedding ring may be worn on either side of the shank. The wedding ring 17 as shown in Fig. 2, by reason of this construction, fits snugly against the shank and under the inclined portion 16, 16^a, of the crown, without any space therebetween to mar the continuity and ornamental appearance of the two rings when worn together, and the combined effect of the two rings is both comfortable to the wearer and affords a neat and harmonious finger ornament.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent—

A ring comprising a complete annular shank of the same cross-sectional size and shape throughout and having side surfaces

lying in parallel planes, and a crown setting permanently secured only at a portion of the outer curved peripheral surface of the annulus, and having the bottom portions of said crown setting projecting outwardly and away from a central axis through said annulus in opposite directions beyond the

side surfaces of the shank to permit the abutment of a plain band ring against either side of the shank throughout its entire surface.

In testimony whereof I affix my signature.

DAVID G. HAY.
